UNITED STATES PATENT OFFICE.

LAWRENCE MORAN, OF CHICAGO, ILLINOIS.

DROP-CORD HOLDER.

Application filed October 5, 1925. Serial No. 60,529.

To all whom it may concern:

Be it known that I, LAWRENCE MORAN, a citizen of the United States, residing at Chicago, in the county of Cook and State 5 of Illinois, have invented certain new and useful Improvements in a Drop-Cord Holder, of which the following is a specification.

The present invention relates to a holder for the drop cord of an electric light, and 10 has for its object to provide a means whereby the electric light may be raised and lowered so as to be held at the desired height.

Another important object of the invention 15 is to provide an adjustable holder of this nature which is exceedingly simple in its construction, strong and durable, efficient and reliable in operation, easy to manipulate, and otherwise well adapted to the purpose for which it is designed.

With the above and numerous other objects in view as will appear as the description proceeds, the invention resides in certain novel features of construction, and in 25 the combination and arrangement of parts as will be hereinafter more fully described and claimed.

In the drawing

Figure 1 is an elevation showing a drop 30 cord and my improved holder associated therewith,

Fig. 2 is a detail perspective view of the holder, and

Fig. 3 is a transverse section therethrough.

Referring to the drawing in detail, it 35 will be seen that 5 designates a bracket of angular construction to provide the top horizontal arm, 6 and the vertical arm 7 depending therefrom. The arm 7 is provided with a longitudinally extending series 40 of teeth 8 which are stamped along the longitudinal dimensions thereof. A carriage A, is formed from a single strip of metal bent to provide jaws 9 for slidably engaging 45 the side edges of the arm 7 and an intermediate offset body portion 10. A clamp 11 is fixed to the body portion 10 of the carriage A.

A spring pawl 12 is fixed to the body 50 portion 10 and its free end engages the teeth 8 for holding the carriage in different adjusted positions on the arm 7. A stop pin 13 is provided on the arm 7 adjacent the upper end of the series of teeth 8, with which the carriage A abuts in its uppermost position. A guide tube 14 pierces the top of the arm

7, extending transversely thereof and having downwardly curved ends 15. A cord or the like 16 is trained through the guide tube 14, through an eye bolt 17, fastened adjacent 60 the free end of the spring pawl and the end of the cord is fastened to the fixed end of the pawl 12, as at 18.

The extension or drop cord 19 depends in the usual manner from the bracket 20 and has the electric lamp or bulb 21 mounted on the end thereof in the usual manner. An intermediate portion of this drop cord 19 is engaged in the clamp 11. By pulling downwardly on the free end of the cord 16, the carriage may be moved upwardly 65 of the arm 7, since when the cord 16 is pulled it will become taut thereby releasing the pawl 12 from the teeth 8. As soon as the cord 16 is released, the spring pawl will 70 move back in place in engagement with the teeth 8 so as to hold the carriage in its adjusted position. To pull the carriage down, it is only necessary to pull downwardly on the cord 16 with sufficient force to cause 75 the pawl 12 to slide over the teeth 8, then reduce the pull on the cord 16 to just enough to hold the spring pawl open and the carriage due to its weight, which is greater than 80 the pressure required to hold the spring pawl open, will slide down to the required position.

It is thought that the construction, operation, and advantages of this invention will 85 now be clearly understood without a more 90 detailed description thereof. The present embodiment of the invention has been disclosed merely by way of example since in actual practice it attains the features of 95 advantage enumerated as desirable in the statement of the invention and the above description.

It is apparent that changes in the details 100 of construction and in the combination and arrangement of parts may be resorted to without departing from the spirit or scope of the invention as hereinafter claimed or sacrificing any of its advantages.

Having thus described my invention, what 105 I claim as new is:—

1. A device of the class described including a bracket having a series of teeth formed thereon, a carriage slidably mounted on the bracket, a spring pawl on the carriage engageable with said teeth, a clamp on said carriage for engaging a drop cord, an eye 110 on the intermediate portion of the pawl,

a cord fixed to the carriage and threaded through the eye, and guide means on the bracket for the cord so that when said cord is pulled to raise the carriage it will pull 5 the pawl out of engagement with the teeth.

2. A device of the class described including a bracket having an upper horizontal arm and a vertical lower arm, said vertical arm provided with a longitudinally disposed series of teeth, a carriage slidably 10 mounted on the vertical arm, a spring pawl on the carriage engaged with said teeth,

a clamp on said carriage for engaging a drop cord, and an eye on the pawl, a guide tube extending transversely through the 15 upper end of the vertical arm, a cord trained through said tube and having one end extending through the eye of the pawl, and fixed to the carriage whereby said cord may be pulled to release the pawl from the teeth 20 and raise the carriage; or lower same.

In testimony whereof I affix my signature.

LAWRENCE MORAN.
